(57) **CLAIM**

The ornamental design for a ride-on vehicle for children as shown and described.

DESCRIPTION

FIG. 1 is a front, right, top perspective view of a ride-on vehicle for children showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 1; and,

FIG. 10 is an enlarged view of the encircled area 10 of FIG. 7.

The broken lines shown on the drawings depict portions of the ride-on vehicle for children that form no part of the claimed design. The dot-dash lines depict the enlarged view boundaries that do not form part of the claimed design.
